UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

ELECTRIC SWITCH.

1,010,425.

Specification of Letters Patent.

Patented Dec. 5, 1911.

Application filed March 20, 1909. Serial No. 484,646.

To all whom it may concern:

Be it known that I, EDWARD M. HEWLETT, a citizen of the United States, residing at Schenectady, county of Schenectady, State of New York, have invented certain new and useful Improvements in Electric Switches, of which the following is a specification.

My invention relates to electric switches, particularly disconnecting switches of the type used to divide a high potential transmission line into sections, and its object is to provide a switch which is suitable for mounting on the top of a tower or pole of a transmission line, in which the contacts are protected from the weather when the switch is either open or closed, which gives a wide gap between the contacts when the switch is open; which is easily operated by means of a comparatively small movement of the actuating member; and which is so constructed that a number of switches may be mounted on the top of a tower or pole of a transmission line and side by side in alignment with the conductors which they control without reducing the space between adjacent phases to a dangerous extent.

In carrying out my invention, coöperating contacts are arranged to move relatively to each other and a cover is provided for protecting the contacts from the weather when the switch is closed. A casing is also provided into which one of the contacts is withdrawn when the switch is opened and the operating mechanism for moving the contacts is also inclosed and thereby protected from sleet and snow.

In the preferred construction, one of the contacts is mounted to reciprocate into and out of a tubular casing mounted in alignment with the conductor to which the switch is connected, the contact being reciprocated by means of a rotatable operating member, preferably an insulator, which is operated from the ground and is connected to the reciprocating contact in such a manner that a comparatively slight angular movement of the insulator will cause an extended movement of the reciprocating contact. The switch is made long and narrow and all the live parts are so arranged that when a number of switches are mounted side by side in alignment with the conductors which they control the space between the live parts of adjacent phases is practically the same at

the switches as it is at other parts of the transmission line.

My invention will best be understood in connection with the accompanying drawings, which illustrate one of the various forms in which my invention may be embodied and in which—

Figure 1 is a side view in elevation of a switch for one conductor of the transmission line; Fig. 2 is an end view of the switch shown in Fig. 1; Fig. 3 is a view partly in section of the protecting casing for the reciprocating contact and the gearing by means of which the rotatable insulator actuates the contact; Fig. 4 is a cross-section of Fig. 3 with the pinion and gearing shown in elevation; Fig. 5 is a plan view of the mechanism shown in Fig. 4, with the protecting casing and the reciprocating contact removed; Fig. 6 is a longitudinal section of one end of the tubular casing into which the reciprocating contact is withdrawn; Fig. 7 is a cross section along the line 7—7 of Fig. 6; Fig. 8 is an end view showing three switches mounted side by side to control a three phase transmission system; Fig. 9 is a bottom view of Fig. 8, showing the gearing for the simultaneous operation of the switches; Fig. 10 is a longitudinal section of the fixed contact and cover; and Fig. 11 is a longitudinal horizontal section of the cover over the fixed contact with the fixed and movable contacts shown in elevation.

In the specific form of switch shown in the drawings, a base 1 of any material suitable for mounting on a tower or pole of the transmission line supports stationary insulators 2 and 3 of any suitable type which will resist the pull of the conductors of the transmission line and properly insulate the conductor. The circuit is controlled by means of relatively movable coöperating contacts of any suitable kind, mounted on the insulators 2 and 3 and in the preferred form of construction, a cover 4, mounted upon the insulator 2, contains the fixed or stationary contact 5, which preferably is made in the form of a contact clip having two spring blades, as best shown in Figs. 10 and 11. The cover 4 is so arranged that it completely incloses and protects the fixed contact against sleet, snow or other deposits which would interfere with the operation of the switch. The fixed contact coöperates

with a movable contact 6 mounted to reciprocate in alinement with the transmission line conductor controlled by the switch, the movable contact being preferably made of 5 angle-iron as best shown in Fig. 7, and provided with a contact tip for engaging the blades of the clip contact 5. The movable reciprocating contact is supported and guided on the stationary insulator 3 by 10 means of a block 7, and in the specific arrangement shown in the drawing, a clamping member 8 holds in firm engagement with the block 7 a casing 9, into which the reciprocating contact 6 is withdrawn as the 15 switch is opened. The casing 9 is mounted horizontally and in alinement with the conductor of the transmission line and is preferably made of a piece of iron tubing of sufficient size to inclose the reciprocating 20 contact 6. In order to assist in breaking any arc which might be formed in case the switch is operated to open the circuit while current is flowing, horns 10 are secured to the cover 4 and the clamping block 8 and are bent 25 away from each other to act like a horn break lightning arrester.

The reciprocating contact 6 is mounted in the casing 9 in any suitable way to slide longitudinally of the casing and to remain 30 in electrical connection with it. In the preferred construction, a grooved guide wheel 11 journaled in the block 7 acts as a support for the reciprocating contact and also maintains the contact in electrical connection with 35 the block 7 and the casing 9. The reciprocating contact is provided with a bar 12 arranged longitudinally of the contact and of a shape to fit in the groove of the guide wheel 11, the bar being provided with teeth 40 to form a rack and connected to the contact by means of a supporting strip 13, riveted to the bar and to the contact as shown in Fig. 4. The contact is held with the bar in the 45 groove of the guide wheel 11 by a holding wheel 14 mounted in the clamping member 8, in a position to engage the reciprocating contact, as shown in Fig. 7.

The movable contact 6 may be reciprocated in any suitable manner but since the 50 contact and the horizontal casing 9 are alive at the potential of the transmission line, the preferred arrangement for actuating the movable contact comprises an insulator 15 of suitable mechanical and dielectric 55 strength mounted for angular movement about an axis and preferably mounted, as shown in the drawings, to rotate about a vertical axis which is at right angles to the horizontal casing 9 and intersects the line of 60 movement of the reciprocating contact 6. The preferred construction comprises a vertical shaft 16 suitably journaled in the base 1 and extending down to a point where an operating handle 17 can be attached at a 65 height convenient for the operator. Suit-

able connections are provided between the insulator 15 and the movable contact for reciprocating the contact and thereby opening and closing the switch when the vertical shaft 16 is rotated by means of the operating 70 handle 17.

Where a number of the switches are mounted side by side, as is customary in polyphase transmission lines, it is desirable that all the switches be operated simultaneously at one movement of the operating handle, and in accordance with my invention, this result is attained by gearing the rotatable insulators of all the switches together by any suitable gearing, such as sprocket 75 wheels 18 and chains 20, shown in Fig. 8, so that when the vertical shaft 16 of one switch is rotated, the corresponding shafts of the other switches are rotated at the same time and to the same extent. 85

In order to secure a quick movement of the switch, it is desirable that a comparatively slight angular movement of the rotatable operating member or insulator 15 should cause the reciprocating contact 6 to move 90 over a distance of several feet and in accordance with my invention the rotatable insulator is connected to the reciprocating contact through some form of gearing or other suitable connection which will cause the reciprocating contact to move through a distance which is greater than the chord of the arc described by the rotatable insulator. It is also desirable that the lateral dimensions of the gearing between the rotatable insulator and reciprocating contact be kept as 95 small as possible, in order to permit several switches to be mounted side by side in alinement with the conductors without reducing the space between the live parts of the 100 switches to such an extent that there is danger of arcing between the phases. Various forms of gearing may be used to secure this result, but in the preferred construction, which I have shown in the drawing, the reciprocating contact is actuated by means of a contact actuator, such as a gear wheel 20 mounted upon the upper end of the rotatable insulator 15 and meshing with suitable gearing, such as a gear 21 which in turn is rigidly secured to a pinion 22 in mesh with the rack bar 12 on the reciprocating contact 6, the parts being so proportioned that the travel of the contact is greater than the length of the arc through which any point 110 on the circumference of the contact actuator or gear wheel 20 moves. The gear and pinion are suitably journaled in a block 23, mounted in alinement with the axis of the rotatable insulator 15 and held in definite 115 relation to the gear wheel 20 by means of a flange 24, engaged by rollers 25 on the gear wheel 20, as shown in Fig. 4. The block 23 is prevented from moving laterally by means of an annular projection 26 co-operating with 120 125 130

a corresponding annular groove cut in the bottom of the gear wheel 20 and its upper end is rigidly secured to a bell shaped cover 27, which incloses and protects the gearing 5 and overlaps the gear wheel 20, as shown in Fig. 8, to such an extent that foreign substances cannot be carried into the gearing. The cover 27 fits into an opening 28 in the lower side of the horizontal casing 9 and 10 practically fills said opening, so that there is no opportunity for foreign substances to be carried into the casing. The cover 27 is held in definite relation to the horizontal casing 9 by means of a clamping yoke 29, 15 which binds the casing between the yoke 29 and the cover 27. The reciprocating contact and the rack bar 12 are held in definite relation to the pinion 22 by means of a grooved holding wheel 30 journaled in the clamping 20 yoke 29 and engaging the upper edge of the reciprocating contact.

The operation of the switch is as follows:—When the circuit is closed, the contacts are in the position shown in Fig. 1 and 25 both the fixed and movable contacts are protected against the weather by the cover 4 which substantially incloses them. If it is desired to open the switch, the vertical shaft 16 is rotated through a definite angle 30 by means of the operating handle 17, thereby imparting an angular movement about the vertical axis to the insulator 15, which partially rotates the gear wheel 20 and in turn rotates the gear 21 and pinion 22. 35 Since the pinion is in mesh with the rack bar 12 of the reciprocating contact, the relation between the angular movement of the insulator 15 and the distance traveled by the reciprocating contact depends upon the proportions of the gear wheel 20, the gear 21 and the pinion 22, which meshes with the rack, and all these proportions can be varied 40 as desired to make the distance through which the reciprocating contact is moved in response to the definite angular movement 45 of the insulator 15 as great or as little as desired. When the switch is fully open, the movable contact is completely covered by the casing, as shown in Fig. 6, and is protected 50 from the weather. The rack 12 and the gearing are both thoroughly protected at all times against the introduction of foreign substances. Since the form of gearing shown is very compact and the lateral 55 dimensions of the cover 27 are not great, the reduction in striking distance between adjacent phases due to the presence of the casing 9 and cover 27, both of which are alive, is so slight that the switch can be installed 60 in alignment with the conductors of a polyphase system without danger of arcing between phases on account of the live parts of the switches being in too close proximity. When the switch is to be closed, a slight 65 movement of the insulator 15 in the reverse

direction will project the reciprocating contact from the casing 9 and bring it into the cover 4, where it engages the fixed contact 5 and closes the circuit.

My invention may be embodied in many other forms than that shown and described and I therefore do not wish to be restricted to the precise arrangement disclosed but aim in the appended claims to cover all modifications within the spirit and scope of my invention.

What I claim as new and desire to secure by Letters Patent of the United States, is:—

1. In an electric switch, the combination 80 with relatively movable coöperating contacts, one of which is mounted to reciprocate, of a contact actuator mounted for angular movement about an axis which intersects the line of movement of said reciprocating contact, and connections of substantially the same width as said actuator between said actuator and said reciprocating contact for rendering the travel of said contact greater than the length of the path 90 traversed by said actuator.

2. In an electric switch, the combination 95 with relatively movable coöperating contacts, one of which is mounted to reciprocate, of a rotatable actuator for said reciprocating contact mounted to rotate about an axis which is perpendicular to and intersects the line of travel of said reciprocating contact, and gearing between said actuator and said contact for rendering the travel of 100 said contact greater than the length of the arc described by said actuator.

3. In an electric switch, the combination 105 with relatively movable coöperating contacts, one of which is mounted to reciprocate and has teeth thereon to form a rack, of a movable actuator for said contact mounted for angular movement about an axis which intersects the line of movement of said reciprocating contact, and gearing controlled 110 by said actuator and in mesh with said rack for moving said reciprocating contact a distance greater than the length of the arc described by said actuator.

4. In an electric switch, the combination 115 with relatively movable coöperating contacts, one of which is mounted to reciprocate, of a contact actuator mounted for angular movement about an axis perpendicular to and intersecting the line of movement of said reciprocating contact, and connections between said actuator and said contact of substantially the same width as the actuator arranged to render the travel of 120 said contact different from the length of the arc described by said actuator.

5. In an electric switch for polyphase circuits, the combination with relatively movable coöperating contacts for each phase, one of said contacts in each phase being 130

mounted to reciprocate, of actuators corresponding in number to said reciprocating contacts mounted for angular movement about an axis, which intersects the line of movement of said reciprocating contact, and connections of substantially the same width as said actuators between an actuator in each phase and a reciprocating contact in the same phase whereby the travel of each contact is rendered greater than the length of the arc described by its actuator.

6. In an electric switch for polyphase circuits, the combination with relatively movable coöperating contacts for each phase, one of said contacts in each phase being mounted to reciprocate, of a contact actuator for each reciprocating contact mounted for angular movement about an axis, which intersects the line of movement of said reciprocating contact, and gearing of substantially the same lateral dimensions as said contact actuator connected between an actuator in each phase and a reciprocating contact in the same phase to render the travel of said contact greater than the length of the arc described by said actuator, and connections between said actuators for operating said actuators simultaneously.

7. An electric switch comprising a reciprocating contact, a gear wheel mounted to rotate about an axis perpendicular to and intersecting the line of movement of said contact, and gearing between said gear wheel and said contact for rendering the travel of said contact greater than the length of the arc described by the circumference of said gear wheel, said gearing being of substantially the same dimensions along a line perpendicular to said axis and to the line of movement of said contact as the diameter of said gear wheel, whereby the striking distance between adjacent phases is not reduced by said gearing.

8. In an electric switch, the combination with relatively movable coöperating contacts, one of which is horizontally mounted to reciprocate, of a horizontal casing for inclosing said reciprocating contact when the switch is open and having an opening in the lower wall, a movable actuator vertically mounted to extend into said casing and to have an angular movement about an axis which intersects the line of movement of said reciprocating contact, and gearing in said casing between said actuator and said contact to render the travel of said contact greater than the length of the arc described by said actuator.

9. An electric switch comprising a fixed contact, an insulated casing mounted adjacent said contact, a terminal on said casing, a coöperating reciprocating contact mounted in metallic engagement with said casing to be projected from and withdrawn into said casing, a movable actuator extend-

ing into said casing, and a gearing in said casing between said actuator and said contact whereby movement of said actuator causes said movable contact to reciprocate.

10. An electric switch comprising a fixed contact, a coöperating reciprocating contact and a horizontal tubular casing having an opening in the lower wall and arranged to cover said reciprocating contact when the switch is open, a rotatable actuator vertically mounted to extend into said casing through said opening, and gearing between said actuator and said reciprocating contact whereby rotation of said actuator causes said contact to be projected from or withdrawn into said casing.

11. An electric switch comprising a fixed contact, a horizontal insulated tubular casing having an opening in the lower wall, a coöperating reciprocating contact mounted in said casing in electrical connection therewith and covered by said casing when the switch is open, a rotatable actuator mounted in alinement with said opening and connections between said insulator and said reciprocating contact whereby rotation of said insulator causes said contact to be projected from or withdrawn into said casing.

12. An electric switch comprising two fixed insulators, a fixed contact mounted on one insulator, a coöperating reciprocating contact mounted on the other insulator, a rotatable insulator rotatably mounted in alinement with said fixed insulators, and connections between said rotatable insulator and said reciprocating contact whereby rotation of said rotatable insulator reciprocates said contact.

13. An electric switch comprising relatively movable coöperating contacts, one of which is mounted to reciprocate, an actuator mounted to rotate about an axis perpendicular to and intersecting the line of movement of said reciprocating contact, a gear wheel mounted on the end of said actuator, and means whereby rotation of said gear wheel causes reciprocation of said reciprocating contact.

14. An electric switch comprising relatively movable coöperating contacts, one of which is mounted to reciprocate and has teeth thereon to form a rack, an actuator mounted to rotate about an axis perpendicular to and intersecting the line of movement of said reciprocating contact, a gear wheel mounted on the end of said actuator, a pinion in mesh with said rack, and a gear connected to said pinion and in mesh with said gear wheel.

15. An electric switch comprising relatively movable coöperating contacts, one of which is mounted to reciprocate, an actuator mounted to rotate about an axis perpendicular to and intersecting the line of movement of said reciprocating contact, a gear wheel

mounted on the end of said actuator, a casing arranged to inclose said gear wheel, a pinion journaled in said casing in mesh with said rack, and a gear connected to said pinion and in mesh with said gear wheel.

16. An electric switch comprising a movable contact mounted to reciprocate horizontally and provided with a rack, a gear wheel mounted to rotate about a vertical axis intersecting the line of movement of said contact, a block mounted on said gear wheel and concentric therewith, a countershaft

shorter than the diameter of said gear wheel mounted in said block, a gear on one end of said countershaft in mesh with said gear wheel, and a pinion on the other end of said countershaft in mesh with said reciprocating contact.

In witness whereof, I have hereunto set my hand this 19th day of March, 1909.

EDWARD M. HEWLETT.
